United States Patent Office.

MYRON T. BOULT, OF BATTLE CREEK, MICHIGAN.

Letters Patent No. 100,848, dated March 15, 1870.

IMPROVEMENT IN CARVING WOOD.

The Schedule referred to in these Letters Patent and making part of the same.

To all whom it may concern:

Be it known that I, MYRON T. BOULT, of Battle Creek, in the county of Calhoun, and in the State of Michigan, have invented certain new and useful Improvements in Process for Carving and Ornamenting Wood; and do hereby declare that the following is a full, clear, and exact description thereof, reference being had to the accompanying drawings and to the letters of reference marked thereon making part of this specification.

The nature of my invention consists in the process of carving and ornamenting upon the surface of wood, by means of patterns, forms, or guides, attached to the back of the piece to be so ornamented, as will hereafter be more fully set forth and explained.

Figure 1 is a perspective of guide or form which is to form the pattern.

Figure 2 is a plan view of the carving or ornament which has been cut or carved in the surface of the wood.

Letter A represents a board or surface which is to be carved or ornamented from any desired design.

To the back of this surface there is temporarily attached a board, B, which has the design cut entirely through its surface, as seen in fig. 1, and which is to serve as a guide in moving the surface A against the revolving cutter. This guide may have any kind of a design cut through it, suitable for table legs, casing over windows, panels, or any ornamental work, so that, by following the model on the back, and keeping the

surface pressed against the cutter, any design may be cut into it.

The machine or cutters by which this work is performed may be either such as was patented by me June 15, 1869, or by any other suitable devices.

I am aware that machines for carving and ornamenting wood are known, and that such machines form the figure or pattern upon the wood by the cutters passing through the template, so that the ornamentation and template are on the same side of the board so carved.

My invention differs from said machines in the fact that by my process the template is on the reverse side of the board from where the cutters act on the wood.

A pin upon the machine is passed into the template on the back of the board, which acts as a guide-point for the cutters, to form the pattern required.

Thus it will be seen that my cutters are perfectly free, and the chips are not liable to choke or obstruct the perfect action of the cutters.

What I claim is—

The method herein described for ornamenting and carving wood, substantially as set forth.

In testimony that I claim the foregoing, I have hereunto set my hand this 13th day of November, 1869.

MYRON T. BOULT.
